UNITED STATES PATENT OFFICE.

EDWARD MILLET LESLIE, OF CINCINNATI, OHIO, ASSIGNOR TO KINGSLAND-KAY-COOK MANUFACTURING COMPANY, OF ST. LOUIS, MISSOURI, A CORPORATION OF MISSOURI.

TROLLEY-WIRE COUPLING.

No. 800,584.

Specification of Letters Patent.

Patented Sept. 26, 1905.

Application filed November 20, 1903. Serial No. 181,964.

To all whom it may concern:

Be it known that I, EDWARD MILLET LESLIE, a citizen of the United States, residing at Cincinnati, in the county of Hamilton and State 5 of Ohio, have invented certain new and useful Improvements in Trolley-Wire Couplers, of which the following is a specification.

In the drawings, Figure 1 is a top plan view, and Fig. 2 a longitudinal section on the line 10 2 2 of Fig. 1.

A represents the tubular body of the coupler, which is provided with a slot and boxes or bearings α' , in which are pivotally mounted toothed cams B, adapted to engage and hold 15 the trolley-wires, the cams being mounted in reverse position relatively to each other.

The operation is as follows: The cams are preferably, though not necessarily, thrown out of operative position, the wires inserted, 20 the cams thrown into engagement therewith, and the clamps released. The teeth of the

cams engage the wires, and the greater the pulling strain upon the wires the greater is the grip of the cams.

It is obvious that the wires may be inserted 25 without throwing the cams out of operative position, in which case the operation of the cams is purely automatic.

I claim as my invention—

In a splice of the character described, the 30 combination with a tube having a longitudinally-extending slot at the center thereof, and pins extending through the ends of the slot; of oppositely-arranged dogs pivotally mounted upon the pins and having curved toothed 35 working faces, said dogs being within the slot and normally projected by gravity into the interior of the tube.

EDWARD MILLET LESLIE.
